UNITED STATES PATENT OFFICE.

RICHARD B. BROOKS, OF MARSHALL, MICHIGAN, ASSIGNOR, BY MESNE ASSIGNMENTS, TO BROOKS RUPTURE APPLIANCE COMPANY, OF MARSHALL, MICHIGAN, A CO-PARTNERSHIP CONSISTING OF ELLEN J. BROOKS, LOUIS E. BROOKS, AND HAROLD C. BROOKS.

TRUSS.

Application filed January 14, 1925. Serial No. 2,275.

To all whom it may concern:

Be it known that I, RICHARD B. BROOKS, citizen of the United States, residing at Marshall, county of Calhoun, State of Michigan, have invented certain new and useful Improvements in Trusses, of which the following is a specification.

This invention relates to improvements in trusses.

10 The objects of the invention are:

First, to simplify such a structure and to provide a rubber cushion portion which, while securely held, is readily removable and replaceable without the use of screws 15 and clamp devices, by simple manipulation.

Second, to provide improved means of retaining and supporting the belt and cross strap.

20 Objects relating to details and economies of construction and operation will appear from the detailed description to follow.

I accomplish the objects of the invention by the devices and means described in the following specification. The invention is 25 clearly defined in the claims.

A structure which is a preferred embodiment of the invention is illustrated in the accompanying drawing, forming a part of this application, in which:

30 Fig. I is a plan view of a truss pad and fragments of the belt and cross strap, from the pad side.

Fig. II is a similar view taken from the back or case side.

35 Fig. III is a detail sectional elevation view taken on line 3—3 of Figs. I, II and IV.

Fig. IV is a detail cross sectional view taken on line 4—4 of Figs. I, II and III.

40 Figs. V and VI are front and back views of the invention as applied to an oval pad truss.

In the drawing similar numerals of reference refer to similar parts throughout the 45 several views and the sectional views are taken looking in the direction of the little arrows at the ends of the section lines.

The parts of the drawing will be identified by their numbers. 1 is the belt, 2 is the 50 cross strap, 3 is the back frame or support for the cushion pad having a strap recess 4 for the belt and an aperture 5 for securing the cross strap end. 6 is the hollow rubber cushion pad hemispherical in form and of

comparatively soft vulcanized rubber. Across 55 the hard rubber casing or back 3 is the belt recess 4 with a cross bar 41 embracing the belt 1. The belt is of elastic material and normally slightly wider than this recess so that it effectively engages the case 3 and 60 supports it in position by friction of the sides.

A peripheral flange 31 is on the front face of the casing extended into an inwardly-projecting annular bead 32, forming an annular recess 33, as seen particularly in Figs. 65 III and IV.

The rubber pad 6 is hemispherical and hollow and at its periphery is recessed by external groove at 61 with an outwardly-projecting peripheral bead 62 conformed to the flange 32 and recess 33 of the cushion. The pad, being hollow, is very readily compressed and inserted against the case 3 and allowed to expand so that the beads referred to interlock, retaining the structure very effectively in position with a smooth joint at all points. The rubber portion of the pad can be very readily removed by the hand, thoroughly cleansed and replaced or 70 renewed.

The cross strap 2 is inserted through a transverse recess 5 in the case, the same forming a retaining bar 51 which is preferably slightly reinforced (see Figs. II and IV). 75 The inner end of the cross strap 2 is folded on itself at 21 and retained by a seam of stitches 22. This enlarges the inner end of the cross strap so that it seats within the recess formed between the bar 51 and the 80 body of the case 1, effectively retaining the cross strap in place by a smooth joint. At the same time it is very readily removable.

I have not shown the buckles for these straps, as my invention in no way pertains to them. In Figs. VI and VII I show an oval pad with a back 3' and rubber cushion 6'. The back bar 41' is on the diagonal to receive the belt 1, and the cross strap 2 is retained in the same way as on the circular pad.

10c My improved pad is adapted to use generally, but is especially well adapted to the arrangement of belt and cross strap here illustrated. I therefore desire to claim the same broadly as well as specifically, as pointed out in the appended claims.

Having thus described my invention, what

I claim as new and desire to secure by Letters Patent is:

1. A truss structure consisting of a casing or body provided with a recess designed to receive the periphery of a soft rubber cushion pad and provided with inturned annular flange forming an engaging ring, a hollow rubber cushion pad, the periphery of which is grooved and beaded to conform to and engage the ring of the said casing or body and project to the periphery thereof forming a shoulder, a transverse aperture recess through the back of the case to receive an elastic belt of slightly larger cross section than said aperture, a transverse aperture for the cross strap, and a cross strap disposed therein with its end folded upon itself and stitched to form an engaging portion, coacting as specified.
2. A truss structure consisting of a casing or body provided with a recess designed to receive the periphery of a soft rubber cushion pad and provided with inturned annular flange forming an engaging ring, a hollow rubber cushion pad, the periphery of which is grooved and beaded to conform to and engage the ring of the said casing or body and project to the periphery thereof forming a shoulder, and a transverse aperture recess through the back of the case to receive an elastic belt of slightly larger cross section than said aperture, a transverse aperture for the cross strap, and a cross strap disposed therein with its end folded upon itself and stitched to form an engaging portion, coacting as specified.
3. A truss structure consisting of a casing or body provided with a recess designed to receive the periphery of a soft rubber cushion pad and provided with inturned annular flange forming an engaging ring, a hollow rubber cushion pad, the periphery of which is grooved and beaded to conform to and engage the ring of the said casing or body and project to the periphery thereof forming a shoulder, coacting as specified.
4. A truss structure consisting of a casing or body, a hollow rubber cushion pad carried by said casing, a transverse aperture recess through the back of the casing to receive an elastic belt of slightly larger cross section than said aperture, a transverse aperture for the cross strap, and a cross strap disposed therein with its end folded upon itself and stitched to form an engaging portion, coacting as specified.

In witness whereof I have hereunto set my hand.

RICHARD B. BROOKS.
